CLAIM

The ornamental design for a bidirectional internet protocol communication device, as shown and described.

DESCRIPTION

FIG. 1 is a perspective view of a bidirectional IP communication device including a voice over IP (VOIP) module according to the invention;

FIG. 2 is a right side elevation view of the bidirectional IP communication device shown in FIG. 1;

FIG. 3 is a left side elevation view of the bidirectional IP communication device shown in FIG. 1;

FIG. 4 is a front elevation view of the bidirectional IP communication device shown in FIG. 1;

FIG. 5 is a rear elevation view of the bidirectional IP communication device shown in FIG. 1;

FIG. 6 is a top view of the bidirectional IP communication device shown in FIG. 1; and,

FIG. 7 is a bottom view of the bidirectional IP communication device shown in FIG. 1.

The broken lines shown in the figures are for illustrative purposes only and form no part of the claimed design.
